UNITED STATES PATENT OFFICE

2,173,148

COACH LOCK

Andrew Christian Andersen, Detroit, Mich., assignor to Ternstedt Manufacturing Company, Detroit, Mich., a corporation of Michigan

Application November 11, 1936, Serial No. 110,258

5 Claims. (Cl. 70—264)

This invention relates to coach locks and has for its object a so-called coincidental lock, that is, one in which two or more of the door locks may be coincidentally dogged.

5 It is not broadly new to coincidentally lock several automobile doors by one operation, nor is it new to coincidentally dog several automobile locks in one operation (see Hardesty Reissue No. 19,073). It has also been proposed to coincidentally dog two or more locks mechanically by the aid of the outside door handle. In mechanically dogging two or more locks, it has been found that the ordinary key does not supply sufficient mechanical power to easily operate the connections. Hence, it has been proposed to use a key connection and the reverse rotation of the door handle to effect this object. The present improvement seeks to accomplish the same general result by using an inside dog controller or an 10 outside operated key cylinder in connection with the power furnished by the closing of the door to effect this object.

This invention utilizes the locking principle of the Andersen and Bowlus Patent 2,039,873 in connection with the key operated lock which is normally the front curb door lock. Preferably, the locks on the other doors are also the Andersen and Bowlus type of locks, but this is not necessarily so as it would be possible to equip the 15 other doors with the conventional blocking type of dog or with any other form of so-called free-wheeling handle lock. But we prefer to utilize the Andersen and Bowlus type of lock on all the doors and the explanations will be in connection with such a form of lock.

35 In the drawings:

Fig. 1 is a fragmentary view of a body showing two locks on one side of the car.

Fig. 2 is an enlarged elevation of the two locks 40 in connection with a center body pillar.

Figs. 3 and 4 are sections on the similarly designated section lines of Fig. 2.

Fig. 5 is an elevation similar to Fig. 2 but showing the reverse side of the locks and pillar (the 45 outside of the pillar).

Fig. 6 is a section on the line 6—6 of Fig. 5.

Fig. 6A is a view similar to Fig. 6, but with the 50 striker-pin carrying segment 28 removed.

Fig. 7 is an elevation of the rear side of an 55 Andersen and Bowlus lock equipped with the improved attachment which gives the coincidental locking features to be described.

Fig. 8 is a view of the same lock with the operating parts disengaged to make the outside handle ineffective.

Fig. 9 is a fragmentary elevation of a body showing how the Andersen and Bowlus lock is operated from the outside.

Fig. 10 is a phantom cross section (diagrammatic) of an automobile body showing how our 5 coincidental lock may be used to operate locks on both sides of the car.

Fig. 11 is a longitudinal section of the cylinder lock.

The details of the Andersen and Bowlus lock 10 are described in Patent 2,039,873 and need not be described here except in a general way. These locks are now used on many cars and a great many of the motoring public are familiar with their operation. A snap button or a push pin is used to control the lock on the inside. The lock is of the semi-freewheeling handle type which is desirable to prevent the forcing of the lock from the outside. When one is in the car and desires to protect himself from the so-called "red light 15 bandit" or from other molestation, he snaps on the button or pushes down on the pin. This disconnects the outside handle from the latch bolt and the outside handle turns freely through a part of a turn without operating anything. In 20 order to make this form of locking device safe from accidentally locking one's self out of the car, a cam arrangement is provided so that each time the inside operating handle retracts the bolt or the bolt is retracted by slamming the door closed, 25 the operating parts are automatically reengaged so that the outside handle will retract the latch bolt. This is an old device that has long been used in connection with dogging devices on automobile doors.

35 The Andersen and Bowlus improvement begins here. By an arrangement of operating connections, Andersen and Bowlus have made it possible by suitable manipulation from the outside of the car to prevent the automatic resetting 40 of the operating connections which normally takes place when the door is slammed shut. Hence, when one gets out of the car, opens the door, sets the inside controlling device to the locking position and then slams the door shut and at 45 the same time manipulates this device to prevent a resetting of the operating connections, the door becomes locked without the use of a key. It has been found desirable to have the outside device that prevents the resetting of the operating 50 connection take the form of turning the semi-freewheeling handle down to the position shown in Fig. 9 and then slamming the door shut with the handle in such turned down position. The details of how this is effected are briefly 55

these: Referring to Fig. 5, 1 designates the outside rollback which bears against the lower end of a lever 2, the upper end of which receives pressure from the end of a spiral spring 3 carried on the inside of the sliding latch bolt 4. 5 is a slide pivoted at 6 to the lower end of the lever 2. The other end of the slide when in the position shown in Fig. 5 is adapted to bear against the abutment 7 of the latch bolt and 10 retract the latch bolt when the slide is retracted by means of the outside rollback 1. This slide has a lug 8 which projects through the slot 9 of the lock-setting arm 10. This arm is pivoted at 11 to the rollback casing 12. Its other end is slotted as at 13 through which the button 14 projects to form a guide. 15 is an over center spring which holds the arm either in the extreme upper or lower position when this is operated by the strap 16 connected with the snap button or control lever 17.

With the snap button or control lever 17 in the position shown in Fig. 7, the operating connections are set to retract the bolt but with the operating connections shown in Fig. 8 and the snap button in the down position the outside handle is in its semi-freewheeling condition such as that shown in Fig. 9. If one attempts to retract the bolt with the parts as shown in Fig. 8, the slide simply moves inoperatively from the position shown in the full lines to the position shown in the dotted lines and designated 19. The automatic resetting device consists of the arm 20 which has the cam face 21 adapted to engage under the lug 22 (Fig. 8). When the latch bolt is retracted in any way, whether by the inside retractor (which is not shown) or by means of the latch bolt head riding over the striker, the cam 21 will engage under the lug 22 and snap the lock-resetting arm back to the position shown in Fig. 7. The Andersen and Bowlus invention consists of providing a device to be manipulated from the outside to prevent this automatic resetting operation and specifically consists in simply turning the handle down as shown in Fig. 9 and holding it in this position while the door is closed. This causes the rollback to move the slide from the position shown in Fig. 8, full lines to the position shown in 19 in the dotted line of Fig. 8. Hence, when the bolt is retracted in any manner and particularly by closing of the door, the lug 22 is out of the range of the cam 21 and consequently this cannot throw the lock-setting arm back over center to reestablish the operating connections between the outside handle and the latch bolt.

The present improvement and invention begins here. The end of the lock resetting arm 10 instead of lying behind the selvage plate 23 passes through the selvage plate as shown by the dotted lines of Fig. 5 at 24 and also in Fig. 6A. The end is in the form of a little nub 25 which engages in a slot 26 in the swinging segment 27. A second segment 28 is pivoted on the outside of the swinging segment 27 and is adjustable with respect thereto by the screw and slot connection 29 and 30. This enables the striker pin or interengaging member 31 to be adjusted with respect to the swinging segment to bring it into accurate relation with the motion-transmitting slide 32. 70 This motion-transmitting slide is wrapped around the inside face and two sides of the center pillar 33. See Figs. 2, 3 and 4. The plate 34 (Fig. 3) secured to the center pillar, carries a pair of rivets 35 and these engage in a slot 36 in the motion-transmitting slide. A cover plate for

the slot is afforded by the steel strap 37. This also furnishes the necessary friction to keep the slide in either of its positions of travel. The slide is provided on each side with a pair of flared mouth keeper sockets designated 38. These are 5 adapted to receive the striker pin 31.

The operation is as follows: One opens either of the doors on one side of the car for the purpose of getting out, this automatically resets the operating connections provided the inside controlling lever has been set. When the door is opened, one sets the inside button 17 to the "on" position which is that shown in Fig. 8. This depresses the inside end of the lock setting arm 10 and it raises the outside arm with the striker pin 31. If the door is open, this pin will not be in contact with the motion-transmitting slide 32. The other door will have the pin 31 engaging the flared socket at the motion-transmitting slide as shown in Fig. 4. With the pin 31 now in 29 the "up" position as shown by the dotted lines designated 39 in Fig. 2, the pin when the door is closed, will strike the upper flare or cam 40 (see Fig. 4). This will cause the slide to rise as shown by the dotted lines 41 in Fig. 2. This will 30 carry the other striker pin together with the swinging segments 27 and 28 of this lock to the upper position, thereby raising the outer end of the setting arm 10 and pressing down the inner end of the arm 10 and thereby disconnecting the 30 operating connections from the other latch bolt. Slide 5, when the outside door handle is turned, will pass to the dotted line position shown in Fig. 8 and designated 19. In this position, slide 5 and consequently lever 10 and striker pin 31 are 35 locked because the lug 22 on slide 5 engages under the turned over lug of the lock casing. Hence, the striker pin 31 is capable of throwing all the parts, including remote connections, without being displaced. Hence, here one has the two locks 40 on one side of the car both locked when one lock is locked and in accordance with the principle of the Andersen and Bowlus patent. By using a strong push and pull wire 42, as shown in Fig. 10, this operation can not only lock both the locks 45 on one side but the locks on the opposite side of the car as shown in Fig. 10. It will be necessary to use a reversing lever 43 to reverse the motion so both of the slides will go up together. The showing in Fig. 10 is simply diagrammatic and is 50 not to be taken as the form that the device would take for actual commercial production.

It will be obvious that all the locks, whether there are two or four, will be mechanically shifted when any one of the inside operating buttons or 55 levers 17 is shifted with all the doors closed or when the key 44 (Fig. 11) is operated from the outside to turn cylinder lock 45 which through crank pin 47 shifts the lock bolt 46 of the curb lock (Fig. 5). Since the key is a difficult instrument to turn where there are small locks to be 60 operated, it is possible to provide springs which will tend to return each of the resetting arms to position to retract the bolt when the key provides the small additional power necessary 65 to turn the arm over center.

What I claim is:

1. In a coincidental locking system, the combination with a plurality of locks each provided with a sliding bolt, with an outside handle, with 70 an outside bolt retractor and with means which may be set to prevent the outside handle retracting the bolt, the last means including an interengaging member, of a motion-transmitting member locatable on the center pillar of the body 75

and having a connection with the interengaging member of each of two locks, said motion-transmitting member and the interengaging members arranged so that when one of the interengaging members is properly set and the door is closing, the motion-transmitting member is struck by and caused by the interengaging member to shift and operate on the interengaging member of the other lock to shift such other lock's means for rendering its outside operated handle ineffective to retract the bolt, the said motion-transmitting member comprises a sliding plate provided with cam surfaces and keeper sockets arranged so that the cam surface is struck by one of said interengaging members when one of the doors is closed, causing the sliding member to shift and the keeper socket receiving the other interengaging member to shift that member.

2. In a coincidental locking system, the combination with a plurality of locks each provided with a sliding bolt, with an outside handle, with an outside bolt retractor and with means which may be set to prevent the outside handle retracting the bolt, the last means including an interengaging member, of a motion-transmitting member locatable on the center pillar of the body and having a connection with the interengaging member of each of two locks, said motion-transmitting member and the interengaging members arranged so that when one of the interengaging members is properly set and the door is closing, the motion-transmitting member is struck by and caused by the interengaging member to shift and operate on the interengaging member of the other lock to shift such other lock's means for rendering its outside operated handle ineffective to retract the bolt, the said means which may be set to prevent the outside handle retracting the bolt comprising an operating connection between the rollback and the sliding bolt and a member by which the same may be shifted into or out of connection with the sliding bolt, the said member extending through the selvage plate of the lock to form the interengaging or striker member.

3. In a coincidental locking system, the combination with a plurality of locks each provided with a sliding bolt, with an outside handle, with an outside bolt retractor and with means which may be set to prevent the outside handle retracting the bolt, the last means including an interengaging member, of a motion-transmitting member locatable on the center pillar of the body and having a connection with the interengaging member of each of two locks, said motion-transmitting member and the interengaging members arranged so that when one of the interengaging members is properly set and the door is closing, the motion-transmitting member is struck by and caused by the interengaging member to shift and operate on the interengaging member of the other lock to shift such other lock's means for rendering its outside operated handle ineffective to retract the bolt, the said motion-transmitting member comprises a sliding plate provided with cam surfaces and keeper sockets arranged so that the cam surface is struck by one of said interengaging members when one of the doors is closed, causing the sliding member to shift and the keeper socket receiving the other interengaging member to shift that member.

4. In a coincidental locking system, the combination with a plurality of locks each provided with a sliding bolt, with an outside handle, with an outside bolt retractor and with means which may be set to prevent the outside handle retracting the bolt, the last means including an interengaging member, of a motion-transmitting member locatable on the center pillar of the body and having a connection with the interengaging member of each of two locks, said motion-transmitting member and the interengaging members arranged so that when one of the interengaging members is properly set and the door is closing, the motion-transmitting member is struck by and caused by the interengaging member to shift and operate on the interengaging member of the other lock to shift such other lock's means for rendering its outside operated handle ineffective to retract the bolt, the motion-transmitting member comprising a sliding plate mounted on the center pillar of the body and provided with flared-mouth striker keeper sockets.

5. In a coincidental locking system, the combination with a plurality of locks each provided with a sliding bolt, with an outside handle, with an outside bolt retractor and with means which may be set to prevent the outside handle retracting the bolt, the last means including an interengaging member, of a motion-transmitting member locatable on the center pillar of the body and having a connection with the interengaging member of each of two locks, said motion-transmitting member and the interengaging members arranged so that when one of the interengaging members is properly set and the door is closing, the motion-transmitting member is struck by and caused by the interengaging member to shift and operate on the interengaging member of the other lock to shift such other lock's means for rendering its outside operated handle ineffective to retract the bolt, and means for automatically resetting the connections between the outside handle and the latch bolt when the bolt is retracted and in which the means which may be set to prevent the outside handle retracting the bolt comprises a lock-setting arm which may be prevented from being automatically reset in the closing of the door by turning the outside door handle down.

ANDREW CHRISTIAN ANDERSEN.
